UNITED STATES PATENT OFFICE.

WILLIAM KRIEGER, OF ELMHURST, AND MILTON MOTT, OF MOSCOW, PENNSYLVANIA.

AUTOMATIC DAMPER.

1,220,432.

Specification of Letters Patent. Patented Mar. 27, 1917.

Application filed June 17, 1916. Serial No. 102,134.

To all whom it may concern:

Be it known that we, WILLIAM KRIEGER and MILTON MOTT, citizens of the United States, residing at Elmhurst and Moscow, respectively, in the county of Lackawanna and State of Pennsylvania, have invented certain new and useful Improvements in Automatic Dampers, of which the following is a specification, reference being had therein to the accompanying drawings.

Our invention relates to improvements in automatic dampers for heating apparatus.

The objects of the invention are to provide automatic time release means for regulating the draft induced through the fire door of a stove or furnace; to provide means for effecting a regulation of the draft door and flue damper; and to provide means for rendering the last mentioned means inoperative, and for restoring the same to normal working condition at a predetermined time.

To the accomplishment of the recited objects, and others subordinate thereto, the preferred embodiment of our invention resides in that construction and arrangement shown in the accompanying drawings, hereinafter described, and embraced within the scope of the appended claims.

In said drawings:

Figure 1 is an elevation of the time release mechanism in set position.

Fig. 2 is a perspective view of the furnace illustrating the position assumed by the combustion-controlling devices corresponding to the arrangement of the tripping mechanism shown in Fig. 1.

Fig. 3 is a detail fragmentary sectional view taken along lines 3-3 of Fig. 1.

Fig. 4 is a view similar to Fig. 1 showing the position of the time release mechanism after it has been actuated.

Fig. 5 is a perspective view of the furnace similar to Fig. 2 illustrating the position of the combustion - controlling devices corresponding to the position of the parts shown in Fig. 4, and

Fig. 6 is a detail sectional view taken along lines 6-6 of Fig. 1.

Broadly, our invention consists of a clock 50 having the usual alarm wind, in combination with a shaft carrying a pair of projections, and an arm adapted for engagement with the alarm wind. Hooks or catches are designed for selective coupling with said projections, one of the hooks being connected to the fire door and the other being connected

to the conventional type of thermostatic regulator by suitable flexible devices. A spring operates in conjunction with one of the hooks, and when the release mechanism 60 is actuated by the alarm the spring pulling upon one of the flexible connections closes the fire door, while the other flexible connection becomes disengaged and permits the regulator to resume its work. Either of the 65 combustion - controlling combinations may thus be operated independently or in unison, according to requirements.

Referring more particularly to the drawings, the numeral 5 designates a shelf located 70 at any convenient point as a support for an alarm clock 6, and, with the co-operation of a transverse partition 7, provides sustaining means for certain other mechanism adapted to be operated by the alarm wind 8. This 75 mechanism comprises a shaft 9 carrying a pair of projections 10 and 11, the former having a lateral reduced extension 12 to which is adjustably secured, as at 13, an arm 14. Lock nuts 15 are arranged upon opposite sides of the projections, thus making it possible to vary the position of the arm 14 with respect to the shaft 9, a considerable portion of which is exposed by virtue of the rabbeted front edge 15' of the partition 7. 80 The arm 14 is longitudinally slotted at 16, and a substantially right-angular shaped slide 17 is adjustably held relatively to the slot by the nut and bolt connection 18. 19 is a stop projecting from the base of the shelf 90 for limiting the downward movement of arm 14.

Operating in conjunction with the projection 10 is the curved loop-like terminal 20 of a link 21, the opposite terminal 22 95 thereof being connected to a coil spring 23 supported with relation to the vertical rod 24 by the adjustable clamp 25. An eye 26 is formed at the upper proximal end of the link 21 for the reception of a depending 100 hook 26', corresponding to the oppositely disposed hook 27 which directly engages the projection 11. These hooks 26' and 27 are carried by the flexible connections or cables 28 and 29 respectively, trained over pairs 105 of suitable pulleys 30 and 31. The other end of the cable 28 passes over another pulley 32, and is fastened to the fire door 33 of the furnace 34, while the companion end of the cable 29 is connected to the rear terminal of the lever 35 of the thermostat 36, the forward terminal having a chain con-

nection 37 with the draft door 38 mounted on the lower ash pit door 39. A short chain 40 serves to connect the flue damper 41 to the rear terminal of the lever 35.

- 5 Under normal conditions and before retiring for the night, the fire door of the furnace is slightly opened (see Fig. 2). The clock alarm is then set in accordance with the time in the morning it is desired to have 10 a hot fire, and the slide 17 seated upon the marginal edge of the alarm wind 8, with hook 26' engaging the eye 26 and the loop 20 coupled with the projection 10. The several parts remain in this position until 15 the alarm is sounded, when the retrograde movement of the alarm wind 8 will cause the same to ride from beneath the slide 17 and permit the spring 23 to exert its contractile force and close the door 33 of the 20 furnace.

When employing our invention in the manner just described, the thermostatic regulator is free to operate the lower draft door 38 and the flue damper 41. However, 25 on windy nights or whenever other conditions are conducive to an abnormal draft, it is desirable to check the fire by closing the lower draft door and flue damper, and temporarily suspending the operation of the 30 regulator. This may be accomplished by connecting the hook 27 with the projection 11 at the same time the connection is made with the other combination of combustion-controlling devices, the various parts occupying the position shown in Fig. 1 of the 35 drawings, that is to say, the fire door is ajar and the lower draft door and the damper are closed. Then when the alarm is actuated, the arm 14 simultaneously releases the link 40 21 and the hook 26', thereby closing the fire door 33 as previously explained, and allowing the thermostatic regulator to resume its work.

What is claimed, is:

- 45 1. The combination with a heating apparatus having a fire door, of a support, a projection pivoted to said support, a link adapted for engagement with said projection, a hook co-operating with said link, a 50 connection between said hook and said door, a depending rod, a clamp mounted upon said rod, a spring connecting said link and clamp, and means for rotating said projection to release the link.
- 55 2. The combination with a heating appa-

ratus having a fire door, of a support, a screw-threaded shaft mounted upon said support, a projection carried by said shaft and being longitudinally adjustable thereof, a spring operated link adapted for engagement with said projection, a hook co-operating with said link, a connection between said hook and said door, and means for operating the projection to release said link. 60

3. The combination with a heating apparatus having a fire door, of a support having a rabbeted transverse partition, a shaft extending through said support and partition, a projection carried by the shaft and adjustable longitudinally thereof within the 70 plane of the rabbeted portion of the partition, a spring operated link adapted for engagement with said projection, a catch co-operating with said link, a connection between the catch and the door, and means 75 for moving the projection for releasing said link.

4. The combination with a heating apparatus having a fire door and an automatic regulator for the lower front draft and flue 80 damper, of a support having a pair of rotatable projections, means adapted to be connected to one projection for maintaining the fire door open, means adapted to be connected to the other projection for holding 85 the regulator inactive, said two last means being independent of each other, and means for automatically disconnecting the projections from either or both of said two means.

5. The combination with a heating apparatus having a fire door and an automatic regulator for the lower front draft and flue damper, of a support having a pair of rotatable oppositely disposed projections, independently operable means connecting said 90 combustion-controlling devices with the projections, and means for automatically disconnecting either or both of the projections from said first mentioned means whereupon the fire door is closed and the regulator is 100 restored to working order.

In testimony whereof, we hereunto affix our signatures, in the presence of two witnesses.

WILLIAM KRIEGER.
MILTON MOTT.
